ATTORNEY

UNITED STATES PATENT OFFICE.

JOHN KOSTKA, OF CLEVELAND, OHIO.

CIGAR AND CIGARETTE BOX.

1,345,935.

Specification of Letters Patent.

Patented July 6, 1920.

Application filed September 5, 1919. Serial No. 321,736.

To all whom it may concern:

Be it known that I, JOHN KOSTKA, a citizen of Poland, residing at Cleveland, county of Cuyahoga, and State of Ohio, have invented certain new and useful Improvements in Cigar and Cigarette Boxes, of which the following is a specification.

The object of this invention is to provide a container for cigars, cigarettes or the like, having combined therewith a receptacle for ashes, a reservoir for matches, a surface upon which the matches may be ignited, a device for puncturing a cigar, and means for clipping its end.

This object is attained by the novel construction and combination of parts herein-after described and shown in the accompanying drawings, forming a material part of this disclosure, and in which—

Figure 1 is a perspective view showing a device made in accordance with the invention.

Fig. 2 is a front elevational view thereof, a portion of the front wall being broken away in order to disclose the construction, and

Fig. 3 is a fragmentary vertical sectional view taken on line 3—3 of Fig. 2.

Referring to the drawings in detail, the numeral 10 indicates the base of the container, and 11 the cover portion, the same being actuated by the side and end walls respectively 12 and 13.

Joined to the rigid cover portion 11 and longitudinal extending ends 14 is a movable cover element 15, while upon the opposite side of the box, engaged by the hinges 16 is a partial cover 17.

A partition plate 12 arranged parallel at the front end wall 13, forms a space 19 therebetween, and joining the plate 18 is a longitudinal partition plate 20, extending through the opposite or rear end of the container. The space between the partition plate 20 and side walls 12 may be used to contain cigars, etc., while the space 19 is adapted to receive ashes and other debris so as to avoid soiling the immediate surroundings.

Recesses are formed in the bottom plate 10 one of which is formed to receive a comb 21, and the other a framed mirror 22, while a smaller drilled circular opening is receptive of the shank of a cigar piercer 23, the same extending outward so as to be readily removed when it is desired for use.

Secured upon the cover 11 is a receptacle 24 having a cover plate 25, joined by the hinges 26, so that the cover may be readily raised, the interior being adapted to hold 60 matches which may be struck upon an abrading surface 27, such as a piece of sand-paper resting on the plate 28 and held in position by the clips 29 disposed along its lateral edges.

Formed through the front wall 13 is a circular opening 30, registering with a similar opening formed in a plate 31, attached to the inner side of the wall, these openings being adapted to receive the tip end 70 of a cigar which is cut after insertion by the operation of a pair of oppositely disposed knives 32 and 33 respectively upper and lower, the same being part of levers 34 and 35, connected pivotally by a pin 36 at 75 one end and operating in the manner of shears with respect one to the other.

Another lever 37, pivoted on a pin 38, is drawn up into a normally operative angular position due to the pull of a spring 80 39 at its upper end, while its inner, lower end rests upon the stop pin 40, set in the bottom plate 10, the free end 41 of the lever 34 is curved downwardly and makes contact with the outer edge of the lever 37, 85 while the free end of the lever 35 is provided with a cam shaped terminal 42 contacting with the lower end of the lever 37 and normally drawn thereagainst by a spring 43.

Passing downward through the top 15 90 of the container is a plunger 44 having an operating head or knob 45, the inner end of the plunger making contact with the upper edge of the lever 34, immediately above the opening 30, the construction being such that as the knob 45 is depressed, its downward motion is transmitted directly to the upper shear 32, and due to the peculiar arrangement of the levers the shear 33 is simultaneously raised, shearing the end 100 of the cigar in an obvious manner.

Upon releasing the knob 45 the parts are brought in a normal open position due to the pull of the spring 39.

From the foregoing it will be seen that 105 a convenient and neat appearing device for the use of smokers has been disclosed in which all necessary and desirable adjuncts are combined so as to be readily accessible in addition to certain toilet articles of the 110 nature indicated.

Having thus described my invention what

I claim as new and desire to secure by Letters Patent, is—

In a container of the character described having a plurality of compartments adapted for the reception of various articles of personal usage, a pair of levers pivotally connected at one end, oppositely disposed knives on said levers in one of said compartments, a stop pin, a pivoted actuating lever adapted to rest with its inner, lower end on said stop pin, a spring for drawing the opposite

end of said lever into normal operating position, a cam-shaped terminal on one of said levers, a spring for connecting said cam terminal and said actuating lever, a plunger contacting with its inner end with the upper edge of one of said pivoted levers, and an operating knob on said plunger to operate said knives. 15

In testimony whereof I have affixed my 20 signature.

JOHN KOSTKA.
